UNITED STATES PATENT OFFICE.

EDWARD G. COOK, OF BROOKLYN, NEW YORK.

METAL BARREL.

No. 880,507.

Specification of Letters Patent.

Patented March 3, 1908.

Application filed January 2, 1906. Serial No. 294,318.

To all whom it may concern:

Be it known that I, EDWARD G. COOK, a citizen of the United States, residing at Brooklyn, in the county of Kings and State 5 of New York, have invented a new and useful improvement in Metal Barrels, of which the following is a specification accompanied by drawings, forming a part of the same, in which—

10 Figure 1 is a side view of my improved barrel. Fig. 2 is a central longitudinal section, and Figs. 3 and 4 are detail sectional views on an enlarged scale, showing the method of uniting the sections of the barrel 15 to the rolling hoops.

Similar reference letters and figures refer to similar parts in the different views.

My invention relates to a metal barrel provided with projecting hoops, to facilitate the 20 rolling of the barrel. My improved barrel is constructed of several portions, stamped, rolled or otherwise manufactured from sheet metal into the desired shapes, and the rolling hoops are utilized to fasten these separate 25 parts together to form the completed barrel.

In the accompanying drawings I have shown a barrel formed in three parts, a central annular band 1 and two cup shaped pieces 2 and 3. The cup shaped pieces are alike, and 30 like the annular band are made from sheet metal by stamping, rolling, or in any convenient manner. The sides of the cup shaped pieces 2, 3 are slightly contracted at their closed ends to form shoulders 4, 5, over 35 which the chime hoops 6, 7, provided with interior grooves 8 are slipped. The contracted sides are then expanded by pressure from the inside to fit the interior groove 8, thereby holding the chime hoops 6, 7, on the 40 barrel.

On both sides of the annular band 1 and on the open ends of the cup shaped pieces 2, 3, I form flanges 10 which are fitted to engage the rolling hoops 11 of the barrel, as is 45 hereinafter described.

The rolling hoops, as shown in Fig. 3, are made of any convenient shape in cross section, and are provided with grooves 12 for the entrance of the flanges 10, and also with 50 laterally extended flanges 13 which are turned down, after the flanges 10 are placed in the grooves 12, thereby securing said flanges 10 therein. This may be accomplished, as shown in Fig. 4, by a pair of rolls 55 14 to which pressure is applied by any con-

venient means, not shown, said rolls act in conjunction with each other and compress between them the flanges 13, but I do not wish to limit myself to this method of confining the sections of the barrel to the rolling hoops, as I am aware that other means may be employed for that purpose.

My improved barrel then consists of the two cup shaped ends 2, 3, made from sheet 60 metal in any convenient manner, and one or more annular bands, also formed from sheet metal, with the various portions attached to intervening hoops, preferably by means of the flanges 10. These flanges 10 are fitted 65 in the grooves 12 in the rolling hoops 11, and the flanges 13 on the rolling hoops 11 are then turned down upon the flanges 10. The various pieces of the barrel are thus firmly 70 secured together with water tight joints between them, and the rolling hoops 11 are not only fastened on the barrel, but also serve to hold the sections of the barrel together.

What I claim as my invention and desire 75 to secure by Letters Patent is:—

1. A metal barrel or similar vessel formed of annular sections having outwardly turned flanges at their edges, a hoop connecting said sections provided with a recess in each side to receive said outwardly turned flanges interior 80 flanges on each side of the hoop below the recess projecting inside said annular sections and bendable flanges on said hoop bearing against the outer faces of said outwardly 85 turned flanges of the barrel sections.

2. A metal barrel or similar vessel formed of annular sections having outwardly turned flanges at their edges and a hoop provided with a recess in each side, said recess being of a width sufficient to receive said outwardly 90 turned flanges with the inside wall of said recess in contact with the inside of said annular section said hoop having a pair of bendable flanges bearing against the outer face of 95 said outwardly turned flanges of the barrel 100 sections.

3. A metal barrel or similar vessel formed of annular sections having outwardly turned flanges at their edges, a hoop provided with a recess in each side, said recess being of a 105 width sufficient to receive said outwardly turned flanges with the inside wall of said recess in contact with the inside of said annular section, and means for holding said outwardly turned flanges in said recess.

4. A metal barrel or similar vessel formed

of annular sections having outwardly turned flanges at their edges, a hoop provided with a recess in each side to receive said flanges, with the inside of said annular section in contact with one side of said recess, the periphery of said outwardly turned flange in contact with the other side of said recess and the face of said outwardly turned flange in contact

with the bottom of said recess and means for holding said outwardly turned flanges in the recesses of the hoop.

EDWARD G. COOK.
